LIGHTING SYSTEM FOR TOY VEHICLES

Harry T. Kingsbury, Keene, N. H., assignor to
Kingsbury Mfg. Company, Keene, N. H., a corporation of New Hampshire

Application March 8, 1933. Serial No. 660,074

11 Claims. (Cl. 46—48)

This invention relates to improvements in toy vehicles, and more particularly the invention relates to improvements in an electric lighting system and a switch mechanism for toy vehicles having illuminating means at spaced intervals.

An object of the present invention is to provide a toy vehicle wherein the chassis is adapted to support a battery, conductor and switch mechanism and wherein the battery is adapted to be shifted in the support therefor by the action of the switch mechanism in order to insure a perfect electrical connection.

A further object of the invention is to provide a toy vehicle having light supports and wherein a conductor member is adapted to extend from one light support to another with an intermediate battery connection.

A further object of the invention is to provide, in a toy vehicle of the type referred to, an electrical conductor having resilient connections with the lights and the battery.

A still further object of the invention is to provide, in a toy vehicle of the type referred to, an improved switch mechanism for completing the light circuit wherein the switch is resiliently urged into electrical contact with the battery.

A still further object of the invention is to provide, in a toy vehicle of the type referred to, an electric lighting system wherein the battery is shifted slightly upon engagement with the switch whereby to insure a positive electrical connection.

The invention still further aims to provide an electrically lighted toy vehicle, of the type referred to, which is inexpensive to manufacture, which is thoroughly reliable in operation and which is strong and durable so that it will not be damaged in transportation or in use, whereby to prevent misadjustment of the battery contacts.

These and other objects of the invention will be obvious and will be hereinafter more fully described.

In the drawings:

Fig. 1 is a side elevation showing the completed toy.

Fig. 2 is a bottom plan view of the same with the wheels omitted.

Fig. 3 is a detail side elevation showing the improved lighting system on the chassis of the vehicle.

Fig. 4 is a fragmentary plan view of the same showing one end thereof.

Fig. 5 is an end view, taken along line 5—5 of Fig. 4, showing the switch mechanism and battery.

Fig. 6 is a sectional view, taken along line 6—6 of Fig. 5, showing the spring connection for the switch.

Fig. 7 is a fragmentary plan view showing another form of switch.

Fig. 8 is a side elevation, in section, of the same.

The improvements afforded by the present invention have been illustrated in the drawings as applied to a toy street car, but it is to be understood that the invention may be applied to any electrically lighted toy vehicle. The body portion 10 is provided with light supports 11 in which are inserted light bulbs. The body 10 is secured to a chassis 12 by means of suitable tongues which fit in openings in the chassis. The chassis is provided with a motor 13 and suitable axle supports 14. The battery 15 is inserted in an opening 16 in the chassis which is provided with fingers 17 directed over the opening. A plate 18 having flanges 19 is adapted to support the battery by sliding the flanges 19 thereon into the flanges 20 on the chassis. The battery 15 is loosely mounted for shifting movement which is caused by the switch mechanism to be hereinafter described.

Friction brackets 21 are mounted on the chassis at spaced intervals. A folded insulating member 22 is mounted between the fingers 23 on each of the brackets. An electrical conductor or bus-bar 24 extending substantially the entire length of the vehicle is mounted in the insulating members 22 which are mounted in the brackets 21, which serve to support the bus-bar. The bus-bar 24 is twisted, as at 25 on each side of the battery, to extend in a vertical plane to the lights. Beyond each of the brackets 21 the bus-bar is bent to form resilient ends 26 which are adapted to contact with the light bulb terminals 27. The bus-bar is provided with a current conducting member 28 which has a contact point 29 adapted to engage a terminal of the battery. An insulating member 30 is secured to the chassis to prevent the member 28 from contacting therewith.

The switch mechanism, as shown in Figs. 4, 5 and 6 of the drawings, will now be described in detail. The switch lever comprises a handle portion 31 and a contact portion 32 integral therewith and extending at an angle thereto. A bracket member 33 is provided with an upright portion 33a which has an opening 34 which registers with an opening 35 in the switch handle. A resilient member 36 is provided with an offset portion 37 which passes through the openings 34 and 35 and is adapted to form the pivot about 110

which the switch is adapted to be moved. The opposite end of the resilient member 36 is provided with a tongue portion 38 which is supported in a cut-out portion 39 in another upstanding portion 40 of the bracket 33. The resilient member is bent to form a bearing surface 41 which constantly presses upon the contact arm 32 of the switch, thus insuring a proper contact when the circuit is to be completed inasmuch as the resilient member 36 gives a variable throw to the contact arm 32. The usual eyelet bearing for the switch lever does not afford enough resilience and it often happens that the contact arm becomes slightly bent so that it is impossible to obtain a good contact with the battery terminal. The present arrangement of switch mechanism provides a spring action to constantly urge the contact arm toward the battery and at the same time affords a pivot point about which the switch lever operates. A clip 42 on the portion 32^a is adapted to hold an insulating member 43 between the battery and the bracket 33. The handle portion of the switch lever 31 has an angular portion 31^a adapted to be grasped by the operator for moving the switch. When the switch lever is moved in a counter-clockwise direction (Fig. 5) the contact point 32^a on the portion 32 will engage the terminal 44 of the battery 15 thus completing an electric circuit through the bus-bar 24. The circuit is grounded through the vehicle. When the switch lever is moved to contact the battery terminal 44, there will not be any contact between the bus-bar and switch. The action of the spring 36 urges the contact point 32^a of the portion 32 into tight engagement with the battery terminal, thus shifting the battery in its seat so that the zinc terminal will contact with the point 29 on the conductor 28. Upon breaking the switch contact, the battery, 40 upon use of the vehicle, will shift away from the member 28 so that the switch will again perform its function when the lights are to be turned on. Another form of switch mechanism is illustrated in Figs. 7 and 8. This switch lever comprises a cam surface 45 and a handle portion 46 which is offset to permit operation of the switch from beneath the vehicle. The switch lever is mounted for rotation on the chassis of the vehicle by an eyelet bearing 47. When the switch 45 is moved in a clockwise direction (Fig. 7), the cam surface will engage the battery terminal 44 and urge the battery forward slightly to contact with the point 29 on the conductor 28. The cam surface, in itself, affords a contact portion 50 with a variable throw.

It is thus apparent that the present invention provides a novel lighting system for toy vehicles wherein the battery may be loosely mounted without positive securing means and wherein the switch mechanism is adapted to shift the battery in order to complete the electric circuit through the bus-bar to the light bulbs and grounding through the chassis. The spring clip on the switch mechanism (Figs. 4, 5 and 6) provides a uniform friction on the switch to insure proper electrical contact. Thus the danger of bending any retaining strip is done away with and at the same time, the switch mechanism insures a proper contact by shifting the battery slightly. It is also possible, with the present invention, to accommodate batteries of slightly different lengths due to the resilient switch mechanism which affords a variable throw to the contact arm thereof in order to insure proper contact. The bus-bar supporting brackets and the

switch bracket may be welded or otherwise suitably secured to the chassis of the vehicle.

It is, of course, apparent that minor changes in details of construction may be made without departing from the scope of the invention.

Having thus fully described my invention, what I claim as new and desire to secure by Letters Patent, is:—

1. In a toy vehicle carrying light bulbs spaced apart, a battery, means for loosely mounting said battery on the vehicle, a conductor extending from one light bulb to another, an auxiliary contact adapted to connect one battery terminal with said conductor, and switch means for engaging one battery terminal to shift the battery into electrical contact with said auxiliary contact, said switch means including a movable member having a contact portion which has a variable throw in line with said battery terminal and means for returning said contact portion to a normal position. 85

2. In a toy vehicle, having a chassis and carrying light bulbs spaced apart, means for loosely mounting a battery on said chassis, a bus-bar extending between said light bulbs and having a depending portion adapted to engage one terminal of the battery, and a switch mechanism adapted to engage the other battery terminal, said switch mechanism being adapted to shift the battery whereby to make contact between the other battery terminal and said depending portion on the conductor and including a movable member having a contact portion which is capable of assuming various positions in line with said battery terminal and means for returning said contact portion to a normal position. 100

3. In a toy vehicle carrying light bulbs, means for supporting a battery, a conductor connecting said light bulbs and said battery, and a switch mechanism for operating the light circuit, said switch mechanism including a pivoted lever and resilient means for urging said lever toward the battery whereby to insure a uniform connection. 115

4. In a toy vehicle, having a chassis, a battery, means for supporting the battery on the chassis for shifting movement, a conductor adapted to engage one terminal of the battery and adapted to connect suitable light bulbs therewith, and means for shifting the battery lengthwise to complete the light circuit, said means including a movable member having a contact portion adapted to assume any one of several positions in line with said battery. 120

5. In a toy vehicle carrying light bulbs spaced apart, a battery, means for loosely mounting said battery on the vehicle, a unitary conductor member extending from one light bulb terminal to another, said conductor member having an intermediate contact portion adapted to engage one terminal of said battery, and a switch mechanism including a contact portion having a variable throw in line with said battery terminal whereby to insure proper contact with the other terminal of said battery and means for returning said contact portion to a normal position. 135

6. In a toy vehicle carrying light bulbs spaced apart, a battery, means for mounting said battery on the vehicle, a conductor member extending from one light bulb terminal to another and having an intermediate portion adapted to engage one battery terminal, and a switch mechanism for engaging the other battery terminal, said switch mechanism including a pivoted lever, and a spring member adapted to bear against 145

150

- said lever to normally urge the lever toward the battery terminal.
7. In a toy vehicle carrying light bulbs spaced apart, a battery, means for mounting said battery on the vehicle, a conductor member extending from one light bulb terminal to another and having an intermediate portion adapted to engage one battery terminal, and a switch mechanism adapted to complete an electric circuit, 5 said switch mechanism including a bracket mounted on the vehicle, a lever pivotally mounted on said bracket and adapted to engage the other battery terminal, and a spring member having one end thereof connected to said bracket and having the other end thereof bearing against said lever whereby to urge the same toward the battery terminal.
8. In a toy vehicle carrying light bulbs spaced apart, a battery, means for mounting said battery on the vehicle, a conductor member extending from one light bulb terminal to another and having an intermediate portion thereof adapted to engage one battery terminal, and a switch mechanism to complete an electric circuit, said 20 switch mechanism including a lever adapted to engage the other battery terminal, and a spring member adapted to urge said lever toward the battery and providing a pivotal support for said lever.
9. In a toy vehicle carrying light bulbs spaced apart, a battery, means for mounting said battery on the vehicle, a unitary conductor member extending from one light bulb terminal to another and having an intermediate portion adapted to engage one battery terminal, said conductor member having the end portions thereof bent at substantially right angles to the plane thereof 25
- and having the extreme ends rebent adjacent the right angle end portions whereby to provide resilient ends to engage the light terminals, spaced brackets mounted on the vehicle for supporting said conductor member, and switch means for completing an electric lighting circuit. 30
10. In a toy vehicle carrying light bulbs spaced apart, a battery, means for mounting the battery on said vehicle, a unitary conductor member extending between the terminals of said light bulbs and having an intermediate portion adapted to engage one battery terminal, said conductor having resilient ends adapted to engage the light bulb terminals, spaced brackets mounted on the vehicle and adapted to support said conductor, each of said brackets comprising a base portion and upstanding resilient arms adapted to receive an insulating member and said conductor, and switch means for completing an electric lighting circuit. 35
11. In a toy vehicle carrying light bulbs at opposite ends thereof, a battery, means for mounting said battery on the vehicle between said light bulbs, a unitary conductor member extending between said light bulbs, said conductor member having a depending portion adapted to contact one battery terminal, spaced brackets mounted on said vehicle and adapted to support said conductor member over said battery, and switch means including a contact portion adapted to engage the other battery terminal, said contact portion being capable of assuming several positions in a direct axial line with said battery terminal and means for returning said contact portion to a normal position. 40
